SCALPER

Joseph Gollbach, Sacramento, Calif.

Application June 8, 1953, Serial No. 360,229

5 Claims. (Cl. 209—361)

This invention relates to a scalper and is particularly suitable for separating the green heavy rice straw from the rice.

Heretofore scalpers have been commonly used in the separating of undesirable material from grain and have consisted of horizontally spaced, perforated rotary discs between which the uncleared grain is introduced. A stationary bottom wall extends between the lower peripheral edges of the discs and as the discs rotate the grain that has worked to the bottom wall falls laterally through the perforations in the discs while the long pieces of foreign material, straw etc. is intended to be moved over said bottom wall and to be discharged therefrom. Generally, the above elements are employed in the invention herein described.

Attempts to use conventional scalpers to separate rice from the green heavy rice straw have not been successful for a number of reasons, and shaker screens have been used. However, the vibration resulting from the use of shaker type separators is so extreme as to be detrimental to the buildings in which they are used, and in addition, the desired separation has not been possible.

In the attempts to use conventional scalpers for rice, the green heavy rice straw and rice are fed from an elevator to the scalpers. A feed belt in the elevator runs continuously and the material is fed from the elevator to the scalpers. The discs in the scalpers become clogged up by the rice straw and when this occurs the elevator is choked and unless the system is quickly cleaned to permit the steady movement of the straw and rice the running of the belt in the choked elevator causes heating that would likely result in causing a fire, an occurrence that would be disastrous.

With the present invention, the scalping is continuous and efficient and provision is made to keep the screens or discs clean and to prevent the material from choking the elevator and the scalper itself.

One of the main objects of the invention is the provision of a scalper having improved means and structure for keeping the straw from choking the scalper and the elevator that feeds the same.

Another object of the invention is the provision of effective means in a scalper for relieving the feed means from surplus material fed thereto so that the material will not pack in the elevator or feed device and thus create a hazardous condition.

Other objects and advantages will appear in the description and in the drawings.

In the drawings,

Fig. 1 is a part-elevational and part sectional view of a scalper showing the present invention, the view being taken from a side of the machine with the near side of the scalper housing removed.

Fig. 2 is a sectional view taken substantially along line 2—2 of Fig. 1.

Fig. 3 is a fragmentary top plan view of the feed means of Fig. 1 with certain parts broken away to show structure.

2

Fig. 4 is an enlarged fragmentary sectional view of the upper end of the rake in Fig. 1.

Fig. 5 is a sectional view taken along line 5—5 of Fig. 4.

In detail, the scalper shown in the drawings comprises 5 a housing having a top wall 1 (Fig. 1), front and rear side walls 2, 3, and opposed end walls 4, 5, which walls together may form the frame members for supporting the working parts of the scalper.

Extending between end walls 4, 5, is a main horizontal 10 shaft 6 that extends at its ends through bearings 7 that are carried by said end walls. This shaft has a plurality of pairs of spaced, perforated, circular, vertically disposed discs 8 secured thereon.

Also secured on shaft 6 and slightly spaced from the 15 opposite outer sides of each pair of discs 8 are imperforate circular discs 9. One of the discs 9 is common to the adjacent discs of adjacent pairs as seen in Fig. 2.

An arcuately curved, elongated bottom wall 10 having a transversely inverted U or V shaped strip 11 extending 20 longitudinally thereof, extends across the space between the lower peripheral edges of each pair of discs 8, and to points 12, 13 about at opposite sides of the axis of rotation of discs 8 or of shaft 6. The bottom wall 10 is stationary and is secured at its ends to the main housing, and a slight space is left between the peripheral edges of the discs 8 and the marginal portions of said bottom wall to permit rice to pass. The strip 11 merely prevents the lodgment of rice on the bottom wall by diverting it to the spaces between the edges of the discs and the marginal portions of the bottom wall.

Up to this point the structure described, is virtually standard, except in the usual structure the point 13 where the bottom wall ends is substantially lower.

Extending upwardly from the bottom walls 10 at the 35 level of point 12 is an outwardly inclined bottom wall 15 of a feed chute and a vertical wall 16 is in upward continuation of the upper end of said wall 15 (Fig. 1).

In spaced opposed relation to wall 16 is a front wall 17 and disposed between these walls 16, 17 is a shaft 20 of a feed screw, which shaft is journaled for rotation at its ends in bearings supported by walls 4, 5. Shaft 20 is parallel with main shaft 6; the opposite ends of the blades 21, 22 on said shaft 20 (Fig. 3) terminate at their outer ends adjacent to end walls 23, 24. These walls 23, 24 extend to the discs 8 near the ends of the row of discs on shaft 6, and terminate at their upper ends in free edges 25 that are even with the level of the axis of shaft 20.

Blades 21, 22 meet at the center of shaft 20 and are arranged to move material fed thereto from above in opposite outer directions toward walls 23, 24.

Box like partitions 26 (Fig. 3) block off the spaces between the adjacent pairs of discs 8, so that material sliding down chute 15 will be directed to the spaces between the discs of each pair and will not enter the spaces between the adjacent discs of adjacent pairs.

A gate 30 (Fig. 1) is supported on the downwardly inclined upper sides of the partitions 26 so as to regulate the amount of material fed to the spaces between the discs 8 of each pair. This gate is connected by one or more arms 31 with a shaft 32 that, in turn, extends through said wall 4 and the end of the shaft that projects from said wall 4 is provided with a handle 33 (Fig. 3) for actuation of the gate as desired. The lower the gate is moved on the partitions 26 the less material can be fed to the spaces between the discs 8 of each pair thereof.

A constant relatively slow speed motor 35 is mounted on the housing 1 (Fig. 1) and the drive shaft 36 of said motor carries sprocket wheels 37, 38 thereon.

A chain 39 connects the sprocket wheel 37 with a sprocket wheel 40 on shaft 20 of the feed screw and a chain 41 connects the sprocket 38 with a sprocket wheel

42 on shaft 6. Thus shafts 6, 20 are connected with the motor for actuation by the latter.

The opposite end of shaft 6 carries a sprocket wheel 60 (Fig. 2) and an endless chain 61 extends thereover and in an upwardly inclined direction to a point spaced above and outwardly of the end 13 of bottom wall 10 where said chain extends over sprocket wheel 62 on shaft 45. Shaft 45 also carries sprocket wheels 44 which drive chains 43. Chains 43 extend between each pair of discs 8 and idle around spacers 34 which separate said discs at shaft 6. Shaft 45 is journaled in bearings carried by walls 4, 5. A guard plate 47 extends between the upper run 48 and lower run 49 of chain 43 and around shaft 45 where said chain extends around each of the sprocket wheels 44 (Fig. 4) to prevent straw, etc. from winding around the shaft 45. A cross frame member 53 supports said guard plates, which frame member may extend between the walls 4, 5.

Equally spaced along the chain 43 are outwardly projecting fingers or forks 50 (Figs. 4, 5) which forks are secured to links of said chain.

Hingedly secured to bottom walls 10 at points 13 where said walls terminate at the side of the shaft 6 opposite the feed screw, is an upwardly extending apron 51. This apron is spaced at its uppermost portion below the lower run 49 of chain 43 and may be considered an upward extension of said bottom walls 10. The apron curves outwardly and downwardly to facilitate the movement of straw and the like thereover, and a removable pin 52 held in each of the end walls 4, 5 supports the apron in its upwardly extending position, and upon removal of said pins the apron can be dropped to facilitate access to the discs 8 when desired.

Secured to the top wall 1 and depending therefrom are baffle or guard strips 55 (Fig. 1) that extend past the shaft 6 at the side of the latter nearest the feed screw, and which strips then extend below said shaft. These strips prevent straw from wrapping around the shaft 6 and clogging the discs 8.

In operation the rice and rice straw is fed to the center of the feed screw from an elevator 56 and it is then distributed across the bottom 15 of the feed chute by the screw for passage to between the pairs of discs 8. These discs are rotated to move the straw over the bottom 10 and their inverted U or V shaped upper sides from points 12 to points 13 and then over the apron 51. The rice drops through the perforations in discs 8. The imperforate discs 9 prevent the straw from passing through, and as the straw moves to the chains 43, the fingers or forks 50 on the latter drag the straw over the apron and it is discharged from the scalper.

In the event an excess of material is fed to the feed screw so that it cannot be carried over bottoms 10 with sufficient speed to keep the scalper free, the excess or surplusage will automatically overflow the end plates or walls 23, 24 and neither the elevator nor the scalper will be clogged. This overflow will pass downwardly over the outer sides of the said plates to mingle with the rice that is discharged through the openings in discs 8 or, if desired, it can be kept separate. In any event, the safety feature of having this structure which enables the scalper to be relieved of the surplusage is very valuable since it insures against the clogging of the elevator, and the likelihood of a fire being created due to such clogging.

The provision of the rakes for keeping the perforated discs free from clogging insures efficient clearing of the screens or perforated plates 8.

I claim:

1. A scalper comprising a pair of vertically disposed, horizontally spaced, coaxial, circular, perforated discs supported for rotation about their common axis, an arcuately extending stationary bottom wall extending across the space between said discs along their lower peripheral edges and extending along the peripheries of said discs to points respectively at opposite sides of said axis, feed

means for feeding grain and the like onto said bottom wall at one of said points, means for rotating said discs for movement of their said peripheral edges along said bottom wall to the other of said points, a rake extending between said discs and over the end of said bottom wall at said other of said points, means for moving said rake outwardly from between said discs for drawing straw and other material that was mixed with said grain from the space between said discs and for discharging it outwardly of said space, said rake being an elongated generally horizontally extending endless member providing an upper and a lower flight and outwardly projecting tines on said flights spaced along the lengths of the latter, a shaft supporting said discs for rotation and to which they are secured, said endless member being a chain, a tubular spacer on said shaft between said discs and a second shaft outwardly of said discs supported for rotation, a sprocket wheel secured on said last mentioned shaft and said chain extending over said spacer and said sprocket wheel, the means for actuating said rake being a motor connected with the shaft supporting said discs and with said second shaft.

2. A scalper comprising a pair of vertically disposed, horizontally spaced, coaxial, circular, perforated discs supported for rotation about their common axis, an arcuately extending stationary bottom wall extending across the space between said discs along their lower peripheral edges and extending along the peripheries of said discs to points respectively at opposite sides of said axis, feed means for feeding grain and the like onto said bottom wall at one of said points, means for rotating said discs for movement of their said peripheral edges along said bottom wall to the other of said points, a rake extending between said discs and over the end of said bottom wall at said other of said points, means for moving said rake outwardly from between said discs for drawing straw and other material that was mixed with said grain from the space between said discs and for discharging it outwardly of said space, the end of said bottom wall at said other of said points being positioned at substantially the same level as that of said axis and said feed means including a rotary feed screw extending transversely across the edges of said disc, a feed chute in which said screw is positioned and end walls at the ends of said screw terminating at their upper ends in free edges about even with the axis of rotation of said screw to pass surplus material thereover in the event of an over supply of such material to said screw.

3. A scalper comprising a row of pairs of vertically disposed, horizontally spaced, coaxial, circular, perforated discs, a rotatable shaft supporting said discs for rotation and to which they are secured, an arcuately extending stationary bottom wall for each pair of discs extending across the space between each pair along their lower peripheral edges and extending along the peripheries of the discs of each pair from a point at one side of said shaft to a point at the other side thereof, an inclined feed chute extending upwardly and outwardly from each bottom wall from said one point of each and extending along said row of discs from end to end thereof, a rotary feed screw also extending along said row and from end to end thereof and disposed outwardly of said disc above and adjacent to the upper side of said feed chute, a vertical wall at each end of said chute extending upwardly from the latter and terminating in free upper edges at the ends of said feed screw over which surplus material is adapted to pass in the event of an overfeed of material to said screw and a passageway alongside said vertical wall at each end of said chute for conducting said surplus material to said bottom wall at the end discs of said row of pairs thereof.

4. A scalper comprising a row of pairs of vertically disposed, horizontally spaced, coaxial, circular, perforated discs, a rotatable shaft supporting said discs for rotation and to which they are secured, an arcuately extending

stationary bottom wall for each pair of discs extending across the space between each pair along their lower peripheral edges and extending along the peripheries of the discs of each pair from a point at one side of said shaft to a point at the other side thereof, an inclined feed chute extending upwardly and outwardly from each bottom wall from said one point of each and extending along said row of discs from end to end thereof, a rotary feed screw also extending along said row and from end to end thereof and disposed outwardly of said discs above and adjacent to the upper side of said feed chute, a vertical wall at each end of said chute extending upwardly from the latter and terminating in free upper edges at the ends of said feed screw over which surplus material is adapted to pass in the event of an over feed of material to said screw, a stationary guard plate extending vertically between the discs of each pair to a point below said shaft and said screw.

5. A scalper comprising a row of pairs of vertically disposed, horizontally spaced, coaxial, circular, perforated discs, a rotatable shaft supporting said discs for rotation and to which they are secured, an arcuately extending stationary bottom wall for each pair of discs extending across the space between each pair along their lower peripheral edges and extending along the peripheries of the discs of each pair from a point at one side of said shaft to a point at the other side thereof, an inclined feed chute extending upwardly and outwardly from each

bottom wall from said first mentioned point and extending along said row of discs from end to end thereof, a rotary feed screw also extending along said row and from end to end thereof and disposed outwardly of said disc above and adjacent to the upper side of said feed chute, a vertical wall at each end of said chute extending upwardly from the latter and terminating in free upper edges at the ends of said feed screw over which surplus material is adapted to pass in the event of an over feed of material to said screw, the level of the bottom walls at the ends thereof that are at said other side of said shaft being at approximately the level of said shaft and a rake between each pair of discs extending from said shaft and over the end of each first mentioned point, said rake being movable in direction away from said shaft for discharging straw and the like from between said discs, means mounting said rake for such movement thereof, means for so moving said rake, and means for rotating the shaft carrying said discs for moving such straw over such bottom wall to said rake.
